UNITED STATES PATENT OFFICE.

WILLIAM ROBERT SMITH, OF NEW YORK, N. Y., ASSIGNOR TO THE STANDARD AUTOMATIC SCALE COMPANY, OF SAME PLACE.

COIN-CONTROLLED WEIGHING-SCALES.

SPECIFICATION forming part of Letters Patent No. 437,166, dated September 23, 1890.

Application filed December 12, 1889. Serial No. 333,441. (No model.)

To all whom it may concern:

Be it known that I, WILLIAM ROBERT SMITH, a citizen of the United States, residing at New York, in the county of New York and 5 State of New York, have invented new and useful Improvements in Coin - Controlled Weighing-Scales, of which the following is a specification.

My invention consists, first, in a device for 10 preventing the shock given the indicating mechanism by a sudden movement imparted to the rack-bar by the tension of the weighing-spring; secondly, in a spring - suspending device adapted to prevent the twisting 15 of the spring and its connecting mechanism; thirdly, in a device attached to the coin-receptacle of a coin-operated weighing-scale whereby on the insertion of the coin the indicating mechanism is released and allowed 20 to operate and on a partial upward movement of the rack which actuates the indicating mechanism the latter is locked to prevent a repetition of the weighing without depositing an additional coin.

25 While my improvements are adapted to all spring-scales having a reciprocating rack-bar actuating the indicating mechanism, whether said bar is rigidly attached or not to the platform lever-connections, I have shown them 30 in the accompanying drawings applied to a coin-operated weighing-scales of the class described in Letters Patent No. 365,353, granted Smith and Washburn June 21, 1887, in which the rack-bar is independent—that is to say, 35 has no rigid attachment to any part of the mechanism—and is free to move independently either of the frame or of the bearings.

In the accompanying drawings, which illustrate my invention, Figure 1 is a front elevation of so much of a weighing-scales as is necessary to show my improvement, with the front of the case and the dial removed. Fig. 2 is a side view of the same, partly in section, on the line 2 2 of Fig. 1. Fig. 3 is a view in 45 perspective of the coin-chute with part of one side removed, showing the releasing and locking devices; and Fig. 4 is a view, also in perspective, of the spring-connection between the pinion and the pointer-shaft.

50 A is a rod, to the lower end of which the

lever of the platform-scales is attached, suspended from the frame or case B by a spring C, attached to a rod D, passing through the casing B. The rod D at its lower extremity is secured to the spring C by means of a cap 55 E, fitting over the end of the rod and having a binding-screw e, which screws into a circumferential groove d, made around the end of the rod. By loosening the binding-screw e, the spring C may be turned in either direction. The rod D is screw-threaded where it passes through the case B, so that by turning the nut d', by which it is suspended, the spring C may be raised or lowered. A set-screw D', held by a standard d'', secured to 60 the back of the case, passes through a slot d''' in rod D, preventing the turning of the rod. Any twist in the spring C tending to rotate the rod A is then removed by loosening the screw e in the cap E and turning the 70 cap, as described.

F is a vertically-sliding rack-bar, having teeth f, which engage with the pinion G of the pointer-shaft H. The rack-bar F slides in bearings i i, attached to the plate I, secured 75 to the case B.

a is a stop on the lever-rod A, against which the rack-bar F abuts when it is allowed to fall by the releasing mechanism.

L is a coin-chute, having one of its sides M 80 pivoted at m. Pivoted to the free end of the side M is a latch-bar N, which, sliding in bearings i' on the back plate I, engages with the teeth f' on rack-bar F, to which it is held in its normal position by the spring n, attached 85 to the chute L. The rearward movement of the latch-bar N is limited by the set-screw n', also attached to the chute L. The other side M' of the chute L is also pivoted at m' by means of a lug m'', secured near its upper 90 extremity. The side M' extends inwardly, so as to form, in connection with the side M of the chute when in their normal position, (see Fig. 1,) a receptacle of only sufficient dimensions to retain the coin. The upper extremity 95 of the side M' has a forked-shaped extension O, between the prongs of which is pivoted a weighted lever P, the end p of which rests in its normal position in the notch f'' in rack-bar F, but is arranged to tip up and yield to 100

the teeth f''' in the rack-bar on the descent of the latter, and to engage with them on the ascent of the rack-bar. The locking of the weighted lever and teeth f''' of the rack-bar 5 on the ascent of the latter tilts outwardly the side M' of the chute on the pivot m' , and thus increases the space between the sides M and M' . A set-screw m''' , which passes through a slot in the side M' and fastens into the 10 prolongation of the neck of the chute, limits the outward throw of the side M' , on reaching which the weighted lever yields to the ascent of the rack.

The operation of this part of my invention 15 is as follows: The mechanism being in the normal position shown in Fig. 1, on placing a weight upon the platform of the scales the rod A descends, but the rack-bar F remains in place, being locked by the latch N . The 20 weight is next indicated by introducing a coin into the chute L , which in its fall pushes back the side M against the spring n , and thus withdraws the latch N and allows the rack-bar F to fall until it abuts against the stop a . 25 and indicates the weight by revolving the pinion G and with it the pointer-shaft H and pointer. The coin meanwhile remains in the chute-receptacle. On a partial removal of the weight the rod A begins to ascend, lifting 30 with it the rack F , and causing the weighted lever P to engage with the teeth f''' on the rack-bar. The further rise of the rack-bar then causes the side M' of the chute L to turn on its pivot m' and release the coin in the 35 chute-receptacle, allowing it to fall through. This in turn releases the side M of the coin-chute, which is then pushed back into position by the spring n , causing the latch N to lock the rack-bar against any further descent. 40 On the entire removal of the weight from the platform the rack and connecting mechanism return to their first position, with the end p of the weighted lever P resting in the notch f'' of the rack-bar. In order to prevent the 45 shock to the indicating mechanism due to any sudden movement of the rack-bar, the pinion G is loosely mounted on the pointer-shaft H , but is held in normal relation to the latter by means of a spring g , having one end 50 fastened to the pinion and the other to the shaft, as shown in Fig. 4.

It is evident that upon a sudden upward

movement of the rack F the pinion G is at liberty to revolve more rapidly than the shaft owing to the yielding of the spring, their 55 normal relations being subsequently restored by the tension of the spring drawing them to their normal position.

Having thus described my invention, what I claim as new, and desire to secure by Letters Patent, is—

1. In spring weighing-scales, the combination of the threaded suspending-rod D , slotted at d''' , having the circumferential groove d , the cap E , the set-screw e , spring C , nut d' , 65 set-screw D' , and case B , substantially as set forth.

2. In a coin-operated weighing-scales, the combination, with a rack actuating the indicating mechanism, of a coin-chute having a 70 freely-swinging pivoted side, a coin-receptacle, of which said side forms a part, and connections between said pivoted side and the rack, whereby the ascent of the rack opens the coin-receptacle to allow the coin to drop 75 through, substantially as set forth.

3. In a coin-operated weighing-scales, the combination, with a rack actuating the indicating mechanism, of a locking and releasing latch controlled by the coin, a coin-receptacle, 80 and a connecting device between the coin-receptacle and the teeth on the rack-bar, whereby on the ascent of the rack-bar the coin is released and the locking device is caused to lock the rack from descending. 85

4. In a coin-operated weighing-scales, the combination, with a rack actuating the indicating mechanism, of a coin-chute I , the pivoted side M , the locking and releasing latch N , the pivoted side M' , having the forked extension O , the weighted lever P , and the teeth f''' on the rack-bar, whereby on the insertion of a coin the rack is released and on the ascent of the rack the coin is allowed to drop through and the rack locked against descent, 90 95 substantially as set forth.

In testimony whereof I have hereunto set my hand in the presence of two subscribing witnesses.

WILLIAM ROBERT SMITH.
